(57) CLAIM

I claim the ornamental design for a runner's plaque, as shown and described.

DESCRIPTION

FIG. 1 is a perspective view of a runner's plaque, showing my new design;

FIG. 2 is a front elevational view wherein the broken line structure has been removed for ease of illustration;

FIG. 3 is a rear elevational view thereof;

FIG. 4 is a left-side elevational view thereof, the right-side elevational view being a mirror image thereof;

FIG. 5 is a top plan view thereof; and,

FIG. 6 is a bottom plan view thereof.
